United States Patent Office.

ELISHA T. COLBURN, OF BOSTON, MASSACHUSETTS.

Letters Patent No. 60,694, dated January 1, 1867.

IMPROVED RAILWAY CARRIAGE WINDOW.

The Schedule referred to in these Letters Patent and making part of the same.

TO ALL PERSONS TO WHOM THESE PRESENTS SHALL COME:

Be it known that I, ELISHA T. COLBURN, of Boston, in the county of Suffolk, of the State of Massachusetts, have made a new and useful improvement in Railway Carriage Windows, or the sashes thereof; and do hereby declare the same to be fully described in the following specification, and represented in the accompanying drawings, of which—

- Figure 1 is an inner side elevation; and
- Figure 2, an external view of a window provided with my invention.
- Figure 3 is a vertical and longitudinal section of it.
- Figure 4 is a horizontal and transverse section; and
- Figure 5 is a transverse and vertical section of it, with its auxiliary sashes open.

The purpose of my invention is to insure ventilation of the carriage, and protection of the eyes and face of a passenger or person therein from dust, smoke, or cinders.

In the drawings, A denotes a window frame, which is to be furnished with two sashes, one of which only, viz, that which is movable vertically within the frame, is represented in the figures. This sash is shown at B as having two auxiliary sashes, C C', each of which is to be glazed with one or more panes of glass. The auxiliary sash, C, is to be connected to one of the upright bars of the main sash, B, by means of hinges, a a, so as to enable the sash, C, to be swung outward. The two auxiliary sashes are to be hinged together at their two inner edges. Furthermore, there project outwardly from the sash C' two round studs, b b, one of which goes upward, and the other goes downward from the sash, this arrangement being as shown in fig. 3. Each of them enters a slot, c, made in a piece of metal, d, fixed to the main sash, the slot being arranged parallel to the outer side of the main sash. The window frame has one of its sash-receiving grooves, viz, that marked e, somewhat deeper than the other, or that marked f, the same being to enable the sash, C', to enter such groove, and to extend therein, when closed as well as when open. This is for the purpose of causing the space that there is between the sash and the next adjacent vertical bar of the main sash, when the auxiliary sashes are opened, to be covered by the window frame. To the hinge-pin or rod, g, of the two auxiliary sashes I apply a hasp, E, made like a trunk hasp. It has two catch holes, i k, made through it, one being made in each of its legs. They are to receive a small pin or stud, l, projected upward from the middle of the lower bar of the main sash. The hasp and the pin serve to hold the auxiliary sashes, either opened or closed. When open they stand at an obtuse angle to each other, as represented in figs. 4 and 5, in which case air can enter the carriage, or leave it, through the triangular open spaces which will there be formed between the horizontal bars of the main and auxiliary sashes. In case the stationary main sash be arranged over and in advance of the main sash, the latter may be raised in its grooves, provided the auxiliary sashes be closed; but by arranging the stationary or upper main sash in rear of the lower main sash, so that the latter, while being elevated, may pass up in front of the former, the said upper sash will afford no impediment to the elevation of the lower sash, when the auxiliary sashes thereof may be open. A window may be made by applying the sashes to the window frame in the same manner as the auxiliary sashes, C and C', are arranged with and applied to the main sash B; but for railway car windows I prefer the retention of the main sashes.

I claim the arrangement and application of the auxiliary sashes, C C', with the window sash B, or its equivalent, substantially in manner and by means as specified.

I also claim the combination, as well as the arrangement, of the window frame, the main sash B, and the auxiliary sashes C C', applied together and to the main sash, substantially as specified.

E. T. COLBURN.
